UNITED STATES PATENT OFFICE.

WILLIAM H. PRITCHARD, OF NEW YORK, N. Y., ASSIGNOR TO NATIONAL PATENT COMPANY, OF NEW YORK, N. Y., A CORPORATION OF NEW YORK.

DESIGN FOR A CASING FOR MUSICAL INSTRUMENTS.

No. 38,772.

Specification for Design.

Patented Aug. 27, 1907.

Application filed May 29, 1907. Serial No. 376,447. Term of patent 14 years.

To all whom it may concern:

Be it known that I, WILLIAM H. PRITCHARD, a citizen of the United States, residing in the city, county, and State of New York, have invented a new, original, and ornamental Design for a Casing for Musical Instruments, of which the following is a specification, reference being had to the accompanying drawing, forming a part thereof.

The figure is a perspective view of the casing for a musical instrument showing my design.

I claim

The ornamental design for a casing for musical instrument as shown.

WILLIAM H. PRITCHARD.
